THERAPEUTIC COMPOSITIONS FOR THE POTENTIATION OF BARBITURATES AND ANALGESICS

Arthur Ernest Wilder Smith, 18 Chemin des Lilas Blancs,

Geneva, Switzerland

No Drawing. Filed Jan. 29, 1962, Ser. No. 169,590
Claims priority, application Great Britain Feb. 7, 1961
11 Claims. (Cl. 167—52)

This invention is concerned with improvements in or relating to therapeutic compositions more particularly compositions containing one or more pharmacologically active barbiturates or morphinic analgesics.

This application is a continuation-in-part of my application Serial No. 764,756, filed October 2, 1958, now abandoned.

As is known, pharmacologically active barbiturates and morphinic analgesics suffer from a number of disadvantages which limit their use in therapeutics. Thus, there may be an inconveniently long latent period after administration of a barbiturate before it takes effect and the sedation produced may not be of the required depth or length. The toxicity of some barbiturates is marked and seriously limits the dose which can be administered. Morphinic analgesics also in general possess marked toxic properties, which limits the dose which can be used.

I have now found, however, that compounds of the general formulae set out below markedly potentiate the pharmacological activity of barbiturates and of morphinic analgesics. In the case of barbiturates this potentiation manifests itself by increasing the soporific and/or anti-epileptic effect of barbiturates and also in some cases by shortening the latent period which elapses after the administration of the barbiturate before it takes effect. The compounds mentioned also in general lower the acute toxicity of barbiturates and render the therapeutic indices more favourable. In the case of morphinic analgesics the ratio of analgesic action to toxicity and respiratory depression is increased thereby enabling more powerful analgesic action to be safely achieved.

It is thus possible to formulate barbiturate and morphinic analgesic compositions containing compounds of the general Formulae I—IV which compositions have a far lower rate of toxicity to pharmacological action than the barbiturates and morphinic analgesics themselves, thus enabling the barbiturates and morphinic analgesics to be administered in a lower dose to obtain the same pharmacological effect.

According to the invention, therefore, I provide therapeutic compositions comprising at least one pharmacologically-active compound chosen from the group comprising barbiturates and morphinic analgesics together with one or more compounds of the following general formulae:

10 (in which R, R₁ and R₂ represent alkyl groups having from 1 to 5 carbon atoms, X represents a group ROOC—, a hydrogen atom or a halogen atom and Y is a halogen atom or a hydrogen atom) and/or non-toxic salts thereof.

Suitable non-toxic salts of both morphinic analgesics and the potentiating compound include particularly addition salts with acids which are physiologically compatible at the dosages employed, examples of such acids being hydrochloric, hydrobromic, sulphuric, citric, tartaric, acetic, fumaric, and maleic acids.

20 In the above general Formulae I and IV R is preferably a methyl, ethyl, n-propyl or n-butyl group. In general Formula I R₁ and R₂ are preferably both ethyl groups.

The substituted butyric acid anilides of Formulae I to IV can be readily prepared by reacting the appropriately substituted crotonic acid anilide with an amine R₁R₂NH, such method being described, for example, in my U.S. Patent 2,801,247 and in my British Patent No. 801,405.

25 As specific preferred examples of compounds of general Formulae I—IV which we have found to be particularly suitable for potentiation of the action of barbiturates may be mentioned the following:

30 N-(β -pyrrolidino)-butyryl-p-amino benzoic acid ethyl ester

N-(β -pyrrolidino)-butyryl-p-amino benzoic acid methyl ester

N-(β -piperidino)-butyryl-p-amino benzoic acid ethyl ester

N-(β -piperidino)-butyryl-p-amino benzoic acid n-butyl ester

35 β -Pyrrolidino-butyric acid anilide

β -Pyrrolidino-butyric acid (2:4-dichloro)-anilide

β -Pyrrolidino-butyric acid (4-chloro)-anilide

40 The barbiturate or barbiturates to be included in the compositions according to the invention may be any desired barbiturate such as phenobarbitone, hexobarbitone, secobarbitone, pentobarbitone and butobarbitone. By the term "pharmacologically active" when used herein in relation to barbiturates is meant barbituric acid and related compounds which have a soporific and/or anti-epileptic effect.

45 By the expression "morphinic analgesic" as used herein I mean morphine itself and analgesics structurally and/or pharmacologically related thereto including particularly but not exclusively naturally occurring substances.

50 Analgesics related to morphine include, for example pethidine, codeine, dihydrocodeine, oxymorphone, oxycodeone, dipipanone, dextromoramide, leverphanol, hydro-morphone, hydrocodone, methadone, phenazocine, pro-poxyphene, piminodine and anileridine.

55 The compositions according to the invention may be formulated together with a pharmaceutical carrier or excipient in any convenient form suitable for administration orally, parenterally or in the form of a suppository.

60 Thus, the compositions may be formulated in a form suitable for oral administration either in a solid or liquid form. A particularly suitable solid formulation is as tablets containing the desired barbiturate or morphinic analgesic together with the potentiation compound in an inert tablet base. In liquid form the compositions

65 70 may be made up as a syrup or like preparation, which may if desired contain surface active and/or flavouring

agents, the latter serving to mask any undesirable taste of the active components.

For parenteral administration the compositions can, for example, be made up in liquid form in pyrogen-free water, the active components preferably in such cases being presented in a water soluble form. Surface active agents may be added if desired.

In such formulations, the potentiating compounds can be present as their water soluble salts for example as hydrochlorides, citrates or tartrates, whilst the barbiturates may for example be present as their alkali-metal salts if these are soluble; the morphinic analgesics may be present as their acid addition salts.

The proportion of the potentiating compounds to the barbiturates or morphinic analgesics present in compositions according to the invention can vary within wide limits.

In the case of barbiturates, in general, the ratio of potentiating compound to barbiturate should be at least 0.75 and preferably at least 1.5, advantageously 1.5-3.0 parts by weight, of potentiating compound to 1 part by weight of barbiturate.

In the case of morphinic analgesics, the proportion of the potentiating compounds to the morphinic analgesic is generally in the ratio of 10 to 50 parts by weight of potentiating compound to 1 part by weight of morphinic analgesic. Preferably the ratio is about 15-30:1.

Where the compositions according to the invention contain more than one barbiturate the action of the barbiturates may well be synergistic. In this case the total dose of barbiturates given may well be less, than if only one barbiturate is given, and in such cases the concentration of potentiating compound can be reduced accordingly.

Preferred analgesic compositions include at least one morphinic analgesic together with β -pyrrolidino butyric acid anilide or a non-toxic salt thereof. Preferred salts include the acid fumarate (M.P. 168° C.) and, in particular, the hydrochloride (M.P. 141-2° C.) and the acid maleate (M.P. 125-7° C.).

The following table gives by way of example only factors by which β -pyrrolidino butyric acid anilide potentiates the action of various morphinic analgesics as determined experimentally in rats.

In each case the β -pyrrolidino-butyric acid anilide was given in a fixed dose of 50 mg./kg. body weight intraperitoneally. The values given for potentiation are those by which the original dose of the drug may be reduced to obtain equi-analgesia when the drug is given in combination with β -pyrrolidino-butyric acid anilide.

TABLE

Drug	Potentiation Factor
Morphine hydrochloride.....	5.92
Codeine phosphate.....	6.16
Dihydrocodeine acid tartrate.....	8.75
Pethidine hydrochloride.....	5.39
(+)-Propoxyphene hydrochloride.....	1.98
Sodium aspirin.....	0

NOTE:—These figures were obtained by using the rat-tail pressure method of assessing analgesia (modified from the method of Green and Young, Brit. J. Pharmacol. (1951), 6, 572).

30 groups (approx.) of rats were used, each group containing 10 animals. A mean value was found for each rat by recording the response to five rapid and consecutive pressures on the tail. The ten means thus obtained were used to calculate the group mean response for both untreated animals and those which receive an injection of the analgesic.

In order that the invention may be well understood

the following representative formulations are given by way of illustration only:

Tablets

		Mgs.
5	(1) Phenobarbitone	45
	β -Pyrrolidino butyric acid anilide	75
	Tablet base to 200 mgs.	
10	(2) Butobarbitone	30
	β -Pyrrolidino butyric acid anilide	50
	Tablet base to 150 mgs.	
15	(3) Butobarbitone	40
	N-(β -pyrrolidino)-butyryl-p-amino benzoic acid ethyl ester	60
	Tablet base to 200 mgs.	
20	(4) Phenobarbitone	30
	N-(β -pyrrolidino)-butyryl-p-amino-benzoic acid ethyl ester	50
	Tablet base to 150 mgs.	
25	In the above tablet formulations the mentioned barbiturate can be replaced by hexobarbitone, secobarbitone or pentobarbitone and the potentiating compound by N-(β -piperidino)-butyryl-p-amino benzoic acid ethyl ester.	
25	(5) Dihydrocodeine acid tartrate	10-15 mg., e.g. 10 mg.
	β -Pyrrolidino-butyric acid anilide hydrochloride ¹	200-300 mg., e.g. 200 mg.
	Tablet base to 500 mg.	
30	(6) Levorphenol tartrate	mg. 1.5
	β -Pyrrolidino-butyric acid anilide acid maleate	mg. 300
	Tablet base to 500 mg.	
35	(7) Pethidine hydrochloride	mg. 25
	β -Pyrrolidino-butyric acid anilide acid maleate	mg. 300
	Tablet base to 500 mg.	

¹This constituent may be replaced by the acid maleate (300-325 mg.).

Capsules

		Mgs.
40	(1) Pentobarbitone sodium	25
	N-(β -piperidino)-butyryl-p-amino-benzoic ethyl ester hydrochloride	50
	Orally acceptable liquid base to 150 mgs.	
45	(2) Butobarbitone sodium	40
	N-(β -pyrrolidino)-butyryl-p-amino benzoic acid ethyl ester	60
	Liquid base to 200 mgs.	

Injectable Preparations

50	(1) Morphine hydrochloride	mg. 5
	β -pyrrolidino-butyric acid anilide acid maleate ¹	200-300 mg., e.g. 200 mg.
	Water for injection	ml. 5
55	(2) Methadone hydrochloride	mg. 5
	β -Pyrrolidino-butyric acid anilide acid maleate	300
	Water for injection	ml. 5
60	(3) Pethidine hydrochloride	mg. 25
	β -Pyrrolidino-butyric acid anilide acid maleate	300
	Water for injection	ml. 5

¹This constituent may be replaced by the hydrochloride (230 mg.).

65 (4) A preparation suitable for intravenous injection can be made by dissolving 50 mgs. of phenobarbitone sodium and 70 mgs. of N-(β -pyrrolidino)-butyryl-p-amino benzoic acid ethyl ester hydrochloride in pyrogen free water. The phenobarbitone sodium may be replaced by any other suitable water-soluble barbiturate and any other suitable water-soluble potentiating compound may be used.

Suppositories

200 mg. suppositories can be made by mixing suitable quantities of barbiturate and potentiating compound in a

5

suitable suppository base. A single 200 mg. suppository could have the following constitution:

Mgs.	45	
Butobarbitone	45	
β -Pyrrolidino butyric acid anilide	70	5
Suppository base to 200 mgs.		

I claim:

1. A therapeutic composition comprising at least one pharmacologically active compound selected from the group consisting of barbiturates and morphinic analgesics and an effective amount of at least one compound potentiating the activity of the pharmacologically active compound, said potentiating compound being selected from the group consisting of

10
15

20
25

30
35

and

40
45

in which R, R₁ and R₂ are each alkyl radicals containing from 1 to 5 carbon atoms, X is a member selected from the group consisting of the group ROOC—, a hydrogen atom and a halogen atom and Y is a member selected from the group consisting of a hydrogen atom and a halogen atom.

2. A composition as claimed in claim 1 in which said potentiating compound is present in the form of its water-soluble acid addition salt.

3. A composition as claimed in claim 1 in which the pharmacologically active compound is a barbiturate and from 0.75 to 3.0 parts by weight of said potentiating compound are present for each part by weight of barbiturate present.

4. A composition as claimed in claim 3 in which said potentiating compound is β -pyrrolidino butyric acid anilide.

5. A composition as claimed in claim 3 in which said potentiating compound is N-(β -pyrrolidino)-butyryl-p-amino benzoic acid ethyl ester.

6. A composition as claimed in claim 1 in which the pharmacologically active compound is a morphinic analgesic and 10 to 50 parts by weight of potentiating compound are present for each part by weight of morphinic analgesic.

7. A composition as claimed in claim 6 in which 15 to 30 parts by weight of potentiating compound are present for each part by weight of morphinic analgesic.

8. A composition as claimed in claim 6 in which the potentiating compound is β -pyrrolidino-butyric acid anilide.

9. A composition as claimed in claim 8 in which the β -pyrrolidino-butyric acid anilide is present in the form of its water-soluble acid addition salt.

10. A therapeutic composition comprising at least 70 one pharmacologically active barbiturate selected from

6

the group consisting of phenobarbitone, hexobarbitone, secobarbitone, pentobarbitone and butobarbitone and an effective amount of at least one compound potentiating the activity of the pharmacologically active compound, said potentiating compound being selected from the group consisting of:

in which R, R₁ and R₂ are each alkyl radicals containing from 1 to 5 carbon atoms, X is a member selected from the group consisting of the group ROOC—, a hydrogen atom and a halogen atom and Y is a member selected from the group consisting of a hydrogen atom and a halogen atom.

11. A therapeutic composition comprising at least one pharmacologically active morphinic analgesic selected from the group consisting of pethidine, codeine, dihydrocodeine, oxymorphone, oxycodone, dipipanone, dextromoramide, levorphanol, hydromorphone, hydrocodone, methadone, phenazocine, propoxyphene, piminodine and anileridine and an effective amount of at least one compound potentiating the activity of the pharmacologically active compound, said potentiating compound being selected from the group consisting of

50

(I)

(II)

(III)

(IV)

in which R, R₁ and R₂ are each alkyl radicals containing from 1 to 5 carbon atoms, X is a member selected from the group consisting of the group ROOC—, a hydrogen

atom and a halogen atom and Y is a member selected from the group consisting of a hydrogen atom and a halogen atom.
